UNITED STATES PATENT OFFICE.

JOSEPH GRANZ, OF CHICAGO, ILLINOIS.

DESIGN FOR A CASE FOR COIN-CONTROLLED CLOCKS AND SAVINGS-BANKS.

46,434.

Specification for Design.

Patented Sept. 22, 1914.

Application filed February 14, 1914. Serial No. 818,801. Term of patent 7 years.

To all whom it may concern:

Be it known that I, JOSEPH GRANZ, a subject of the Emperor of Austria-Hungary, residing at Chicago, in the county of Cook and State of Illinois, have invented a new, original, and ornamental Design for a Case for Coin-Controlled Clocks and Savings-Banks, of which the following is a specification, reference being had to the accompanying drawing, forming part thereof.

The figure is a perspective view of a case for a coin controlled clock and savings bank showing my new design.

I claim:

The ornamental design for a case for coin controlled clock and savings bank, as shown.

JOSEPH GRANZ.
